UNITED STATES PATENT OFFICE

96,452

DESIGN FOR A GRAVE MARKER

Jules J. Eck, York, Pa.

Application June 6, 1935, Serial No. 57,172

Term of patent 14 years

To all whom it may concern:

Be it known that I, Jules J. Eck, a citizen of the United States, residing at York, in the county of York and State of Pennsylvania, have invented a new, original, and ornamental Design for a Grave Marker, of which the following is a specification, reference being had therein to the accompanying drawing.

In the drawing:

Figure 1 is a top plan view of a grave marker with the base portion as illustrated in dotted lines in Figs. 2 and 3 omitted, showing my new design.

Figure 2 is a transverse sectional view taken on line 2—2, Figure 1.

Figure 3 is a longitudinal sectional view taken on line 3—3, Figure 2 and looking in the direction of the arrows.

I claim:

The ornamental design for a grave marker, as shown and described.

In testimony whereof I hereunto affix my signature.

JULES J. ECK.
